Primary Examiner — Ian Simmons*Assistant Examiner* — Shannon Morgan(74) *Attorney, Agent, or Firm* — Price Heneveld LLP(57) **CLAIM**

I claim the ornamental design for a neckware, as shown and described.

DESCRIPTION

FIG. 1 is a right-side elevational view of the neckwear showing my new design;

FIG. 2 is a front elevational view thereof;

FIG. 3 is a left-side elevational view thereof;

FIG. 4 is a rear elevational view thereof; and,

FIG. 5 is a bottom plan view thereof.

The broken lines showing a necklace and circular features in the figures are for the purpose of illustrating environment, and form no part of the claimed design.
